No. 674,588.

Patented May 21, 1901.

A. W. STEIGER.

PAPER TENSION FOR TYPE WRITERS.

(Application filed Aug. 20, 1900.)

(No Model.)

UNITED STATES PATENT OFFICE.

ANDREW W. STEIGER, OF BOSTON, MASSACHUSETTS, ASSIGNOR, BY MESNE ASSIGNMENTS, TO AUGUSTUS L. HOFFMAN, FREDERIC S. CONVERSE, AND FREDERIC J. LEACH, TRUSTEES, OF LYONS, NEW YORK.

PAPER-TENSION FOR TYPE-WRITERS.

SPECIFICATION forming part of Letters Patent No. 674,588, dated May 21, 1901.

Application filed August 20, 1900. Serial No. 27,426. (No model.)

To all whom it may concern:

Be it known that I, ANDREW W. STEIGER, a citizen of the United States, residing in Boston, in the county of Suffolk and State of Massachusetts, have invented certain new and useful Improvements in Paper-Tensions for Type-Writers, of which the following, taken in connection with the accompanying drawings, is a specification.

10 This invention in type-writers relates to devices for positioning the paper-table and pressure and guide rolls with relation to the platen, and is particularly applicable to machines in which the platen, paper-table, and appurte-
15 nances are integral and removable from the carriage.

In reviewing the evolution of writing-ma-
20 chines we find an occasional instance in which the pioneer machines were provided with fairly efficient devices for holding the paper to the platen adapted to the somewhat crude state of the machine then. At the present time, however, it has become imperative to so construct the machine that the platen and
25 devices for holding the paper may be quickly removed from the carriage and a different platen substituted for immediate use. It has been common to force the pressure-roll against the platen by means of springs at-
30 tached to the roll, and as the effect of the springs varies along the pressure-roll the paper may not feed accurately. This fault is particularly troublesome if the paper is not perfectly smooth or in case it should be
35 creased or wrinkled more at one side of the center than the other.

Therefore this invention consists, instead of holding the pressure-roll to the platen by springs, of devices to clasp the pressure-roll
40 at each end of the platen exactly parallel thereto.

The platen is made with a carefully-finished rubber surface and is supplied with finger-knurls attached to its shaft for convenient
45 manipulation.

The paper-table consists of a sheet of metal bent about the lower half of the platen and fastened at either end of the platen to reinforcing-strips of metal, which are furnished
50 with trunnions to prevent the paper-table

and connected parts from turning about the platen, the shaft of which and the trunnions are supported in the carriage. The platen and paper-table are maintained in proper relation to each other by hangers pivoted to the 55 trunnions and hooked to suitable bearings on the shaft of the platen. Levers connected at their extremities by a finger-bar are pivoted to the reinforcing-strips and carry pins which enter slots in the hangers to clamp the pres- 60 sure-roll in contact with the platen. The edges of the levers are beveled to form cams, which as the levers are pulled forward come in contact with the disks on the shaft and push the pressure-roll away from the platen. 65 Further motion of the levers allows slight de-
pressions on the levers to surround the disks, and a spring attached to the levers and hangers keeps them in place. When the levers are pushed back beyond the point of contact 70 of the cams with the disks on the platen-shaft, the springs bring the pressure-roll into contact with the platen, and as the levers reach the extremity of their travel the pins fall into the lower portion of the slots in the 75 hangers, and the pressure-roll is positioned and clamped parallel to the platen.

Pivoted in slots in the levers and arranged just beneath the finger-bar is a guide-roll, which is lightly maintained in contact with 80 the paper on the platen by springs connected to the finger-bar. This guide-roll keeps the paper smooth on the platen and prevents defective impressions of the type. When inserting the paper, this roll is pulled forward 85 out of the way.

The invention further consists of the de-
vices and their combinations, which will be pointed out.

In the drawings, all of which are enlarged, 90 Figure 1 is an end elevation of my platen and accessories. Fig. 2 is a like view with the parts in changed relation. Fig. 3 is a front elevation. Fig. 4 is a modification.

The paper-table is held in place in bearings 95 *a* on the carriage by trunnions *b*, projecting from the reinforcing-strips *c*, and at the upper portion of the reinforcing-strips, just beneath the scale, the pressure-roll *d* is pivoted. Hangers *e* hook over bearings on the shaft of 100

the platen *f* and are maintained in position by the trunnions *b*, which pass through the lower portions of the said hangers. The parts connected with the platen are supported from 5 the platen-shaft, which is pivoted at the bottom of the slot *t* of the carriage, as indicated by dotted lines in Figs. 1 and 2, such being the ordinary construction of the Jackson machine. There are cam-levers *g* pivoted to the 10 reinforcing-strips *c* and connected by springs *i* to the hangers to furnish a yielding or floating link attachment between the hangers and levers for purposes that will appear. The levers have beveled edges *j*, which when forced 15 against the bosses *k* on the platen-shaft separate the pressure-roll and platen. As the finger-bar *h* is pulled forward over the scale attached to the reinforcing-strips *c* the slight 20 depressions *l* of the cam-levers *g* just beyond the highest portion of the said beveled edges encircle the bosses *k*, and the springs *i* hold 25 the parts in this position for the easy insertion of the paper. To clamp the pressure-roll parallel to the platen, I insert pins *m* in the levers *g*, and as the levers are restored to 30 their normal position the pins rise over the cam projections *n* of the hangers *e* and sink toward the lower portion of the slots, thus effectually clamping the pressure-roll the same distance at each end from the platen.

Sometimes instead of utilizing the levers *g* to separate the platen and roll I cut slots *o*, with parallel sides, in the hangers, and the pins *m* now both clamp and free the pressure-roll. This construction requires more 35 accurate work, and I find it easier to adjust the parts when the cam projections are on the hangers *e* and the beveled edges on the levers *g* to separate the roll and platen.

40 For the purpose of holding the paper smoothly over the platen I support in slots in the cam-levers *g* a guide-roll *p*, which is lightly pressed against the platen by springs *r*, attached to the finger-bar *h*. The position 45 of the guide-roll *p* to hold the paper is determined by bosses *s* on the trunnions *b*, which limit the backward motion of the levers *g*.

Having described my invention, what I

claim, and desire to secure by Letters Patent of the United States, is—

1. In a type-writer, hangers connected with the platen-shaft, a paper-table having trunnions journaled in the carriage that restrain the hangers from rotation about the platen, levers pivoted to the paper-table, a guide-roll mounted in the levers and devices to press the roll toward the platen, springs tending to hold an extension of the paper-table and the guide-roll in contact with the platen and a latch to position the roll and extension clear of the platen, substantially as described. 50

2. In a type-writer, a pressure-roll arranged in proximity to a platen, cam-levers to separate and hold roll and platen apart, combined with pins on the levers and interlocking cam 55 projections to secure the pressure-roll parallel to the platen, substantially as described. 60

3. In a type-writer, a platen, hangers depending from the shaft of the platen and restrained from rotation about the said shaft 70 by the trunnions of a paper-table, which latter supports a pressure-roll, cam-levers, spring-connected to the hangers, pivoted to the paper-table and adapted to free the pressure-roll, combined with pins on the cam-levers and projections on the hangers, designed to clamp the pressure-roll parallel to the platen, substantially as described. 75

4. In a type-writer, hangers supported from the platen, pivoted levers, connected by a finger-bar, carrying a spring-positioned guide-roll, links and springs connecting the levers with the hangers, combined with means to lock the guide-roll out of contact with the platen when inserting the paper, and means 85 to position the guide-roll and platen to hold the paper when writing, substantially as described. 80

In testimony whereof I have hereunto subscribed my name this 27th day of December, 90 A. D. 1899.

ANDREW W. STEIGER.
